UNITED STATES PATENT OFFICE.

CHARLES F. DERNELL, OF INDIANAPOLIS, INDIANA, ASSIGNOR OF ONE-HALF TO GEORGE H. HERPICK, OF SAME PLACE.

CARRIAGE-TOP JOINT.

SPECIFICATION forming part of Letters Patent No. 340,105, dated April 20, 1886.

Application filed January 18, 1886. Serial No. 188,884. (No model.)

To all whom it may concern:

Be it known that I, CHARLES F. DERNELL, a citizen of the United States, residing at Indianapolis, in the county of Marion and State 5 of Indiana, have invented a new and useful Improvement in Concealed Brace-Joints for Carriage-Tops, of which the following is a specification.

My invention relates to an improvement in 10 the brace-joints usually put in carriage tops, one on each side, between the rear bow and the bow next in front of it, and known in the art of carriage-trimming as "concealed joints." Heretofore a joint of this class has consisted 15 of two straight solid bars hinged together end to end, so as to form a straight-jointed bar, which is adapted to bend in one direction only. Said bar has been pivoted at each end to suitable clips, by means of which it has 20 been secured to the opposed edges of the back bow and the bow next in front in a position parallel with and concealed by the lower edge of the top-covering. When the 25 bar has been secured in this position, its point of attachment to the back bow is at a greater distance from the bow-iron, which forms a common center from which the bows radiate, than its point of attachment to the forward bow, and the bars of which the brace joint is 30 formed, being fixed as to length it has been impossible to fold the bows closely together.

The object of my improvement is to avoid 35 this difficulty, and I accomplish this result by making one of the bars of which the joint is composed extensible, the bar being formed in two parts adapted to embrace each other and slide one upon the other, as hereinafter fully explained.

The accompanying drawings illustrate my 40 invention.

Figure 1 is a side elevation of my improved joint. Fig. 2 is an edge view of the same. Fig. 3 is a side elevation of a carriage-top, showing the position of the brace when the 45 top is extended. Fig. 4 is a partial side elevation showing the relative position of the bows and joint when partly folded. Fig. 5 is a similar elevation showing the bows and joint when completely folded.

50 The brace-joint consists of two bars, A and B, hinged together at c, so as to bend in one

direction. Said bars are pivoted at their free ends to clips d and e, which are for the purpose of securing the brace-joint to the carriage-top bows f and g. Bar A, the hinge c, and clips d and e do not differ from similar parts well known in this class of brace-joints. Bar B is divided longitudinally into two parts, h and i, which are held together so as to slide one upon the other in the direction of their length by suitable clips, j and k. Part h forms a part of the hinge c, and part i is pivoted to the clip d. One or both of the parts h and i is provided with a shoulder, as at l, against which the opposite part abuts when the brace is at its normal length, as shown in Fig. 3. Two joints are used, one at each side of the top.

In operation the brace-joint having the two parts of its extensible bar B closed together and the free ends of the joint secured between bows f and g, as before explained, that portion of the top-covering between the two bows is held extended. When the top is to be folded back, the hinge of the joint is drawn downward, thereby allowing the bows to approach each other until the position shown in Fig. 4 is reached, up to which point the joint does not act differently from those well known and in use heretofore; but at this point further movement in the old device cannot be made on account of the relative position of the hinge c and the pivotal points of attachment of the joint to the bows.

In my improvement, as the bows move 85 from the position shown in Fig. 4 to that shown in Fig. 5, bar B is drawn out or extended, as shown, thus permitting the closer folding of this portion of the top than heretofore.

90 I claim as my invention—

The above-described carriage-top joint, consisting of bar A, clips d and e, and bar B, divided longitudinally into two similar parts, having the clips j and k and shoulder l, all 95 combined and arranged to co-operate in the manner specified.

CHARLES F. DERNELL.
